COMBINATION WINDOW SHADE AND
SCREEN ROLLER

Alfred Zaferakis, Astoria, Long Island, N. Y.

Application July 17, 1940, Serial No. 345,921

7 Claims. (Cl. 160—263)

This invention relates to an adjustable combination window shade and screen roller.

The invention proposes the construction of a roller as mentioned which is characterized by a plurality of telescopically engaged roller tubes having inter-engaging longitudinally extending flutes extending from end to end.

Furthermore, the invention proposes the provision of cup shaped caps set into the outer ends of the outer ones of said telescoping tubes. It is also proposed to provide the caps with prongs adapted to extend into the ends of the flutes for gripping the material of a window shade or screen to secure the same upon the roller tubes.

Still further the invention proposes the provision of a peg centrally mounted on one of the end caps, set inwards from the end of the roller tube in a manner so that a coacting bracket which is mounted on the window frame extends into the cap to engage the peg. The construction permits the edge of the window shade or screen to be very close to the sides of the window.

Still further the invention proposes to mount a non-circular peg on the other of the end caps, arranged in a similar fashion so that a bracket with a non-circular opening, which is mounted on the window frame, may engage the latter peg with the edge of the window shade or screen very close to the side of the window frame.

Still further the invention proposes a novel means for holding certain of the roller tubes in various adjusted positions to make the roller adjustable to windows of different widths.

Another object of the invention resides in the provision of means for resiliently connecting certain of said roller tubes so that the roller may be slightly collapsed to withdraw it from its position on a window frame.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a longitudinal sectional view of a combination window shade and screen roller constructed in accordance with this invention.

Fig. 2 is an end elevational view of Fig. 1 looking from the left.

Fig. 3 is an end elevational view of Fig. 1 looking from the right.

Fig. 4 is a fragmentary enlarged detailed view

of the left portion of Fig. 1, with the roller shown applied to a window frame bracket.

Fig. 5 is an elevational view of the window frame bracket shown in Fig. 4.

Fig. 6 is a fragmentary enlarged detailed view of the right hand end of Fig. 1 with the roller shown applied to the window bracket.

Fig. 7 is an elevational view of the window bracket shown in Fig. 6.

Fig. 8 is a plan view of Fig. 1.

Fig. 9 is a perspective view of the ratchet used at the left hand end of Fig. 1.

Fig. 10 is an elevational view of the window frame bracket shown in Fig. 5 but illustrated in another position.

Fig. 11 is a longitudinal sectional view of a combination window shade and screen roller constructed according to another embodiment of this invention.

Fig. 12 is an elevational view of Fig. 11.

The combination window shade and screen roller, in accordance with this invention, includes a plurality of telescopically engaged roller tubes 10, 11 and 12 having interengaging longitudinally extending flutes 13 extending from end to end. A cup shaped cap 14 is set into the outer end of the tube 10. Another cup shaped cap 15 is set into the outer end of the tube 12.

The cap 14 has a flange 14^a which is extended 30 outwards over the edge of the tube 10. Prongs 16 are welded or in any other manner secured or formed upon the flange 14^a and extend into the ends of the flutes 13 for gripping the edges of a window shade or screen which is mounted 35 on the roller. The cap 14 has a tubular hub portion 14^b. The cap 15 is also provided with a flange 15^a which has several prongs 16 connected therewith and extended into the end portions of the flutes 13 of the tube 12. A peg 17

40 is mounted centrally on the cap 15. This peg is adapted to engage a window frame bracket 18 formed with a circular opening 19 into which the peg engages. The bracket 18 is provided with flange portions 18^a engaged by fastening 45 elements 20 by which the bracket is secured to a window frame 21.

A shaft 22 is rotatively mounted through the hub portion 14^b of the cap 14. A non-circular peg 23 is fixedly mounted upon the outer end 50 of the tubular shaft 22. The outer end of this shaft is formed with a flange 22^a. A ratchet disc 24 is fixedly mounted upon the shaft 22 immediately adjacent the flange 22^a. This ratchet disc engages against the face of the base wall of the cap 14. A collar 25 is fixedly mounted

upon the tubular shaft 22 immediately adjacent the inner end of the tubular hub portion 14^b. Thus the shaft 22 is rotatively supported.

The non-circular peg 23 engages a wall bracket 26 which is formed with a non-circular opening 27 adapted to receive the non-circular peg 23. The bracket 26 is provided with lugs 26^a through which fastening elements 20 are engaged for securing the bracket to the window frame 21.

When the bracket 26 is attached to a window frame in the position as illustrated in Fig. 5 with the round part of the opening 27 at the bottom, then the peg 23 will be held in the position in which the ratchet 24 has the ratchet opening 24^a at the bottom. With this arrangement the ratchet and pawls 28 are inoperative because with the ratchet opening 24^a at the bottom, the pawls are incapable of engaging the opening. The roller is now adapted to be used for a screen, since the screen will then be free to be pulled out or drawn in, depending upon the way the window sash is moved.

If the bracket 26 is turned around so that the rounded portion of the opening 27 is at the top, as illustrated in Fig. 10, then the peg 23 is held in the position so that the ratchet 24 has its opening 24^a at the top. The pawls 28 will now be capable of engaging the opening 24^a of the ratchet which is now operative. With the parts in this position the roller may be used for a window shade. The peg 23 is formed in the small opening 23^a which is used to receive a shaft to assist in winding the spring of the roller.

Pawl and ratchet means is mounted on, with the cap 14 and is cooperative with the shaft 22 to latch the roller in certain "wound" positions. This means includes a pair of pawls 28 which are pivotally supported by pintles 29 on the base wall of the cap 14. These pawls are adapted to coact with the ratchet disc 24. This ratchet disc comprises a disc-shaped element having a cutout 24^a in its periphery into which the tip ends of the pawls 28 are adapted to engage.

A spring 30 is coaxially extended along the shaft 22 and acts between this shaft and the cap 14. More particularly, the spring 30 has an end 30^a which is engaged into a cut 31 formed in the end of the shaft 22. The spring 30 has its other end 30^b engaged through several lugs 32 stamped from the base wall of the cap 14. A fiber tube 33 is mounted around the spring 30 to encase it. This fiber tube has its inner end engaged over the lugs 32 and its outer end supported by several prongs 34 stamped from the bottoms of the flutes 13.

There is means for holding certain of the roller tubes in various adjusted positions. This means includes several H-shaped cutouts 35 formed in the material of the tube 11. A leaf spring 36 has downwardly projecting portions 36^a and is laced through said H-shaped cutouts 35 in a manner so that the projections 36^a resiliently engage certain ones of a group of cutouts 37 formed in a longitudinal line along the length of the roller tube 10.

The arrangement is such that the tubes 10 and 11 may be pulled apart or pressed together, and during the motion thereof the resilient projections 36^a will snap into and out of the openings 37. Thus these roller tubes may be left in any relative position desired.

There is also a means for resiliently connecting certain of the roller tubes. This means comprises a transverse disc 40 extended across a portion of the tube 11 and having a flange 40^a 75

formed with several outwardly projecting prongs 41 engaging small openings 42 formed in the material of the tube 11 to hold the disc stationarily in position. A spring 43 has one end 43^a threaded through loop shaped lugs 44 stamped from the material of the disc 40. The other end 43^b of the spring 43 engages against the base wall of the cap 15 for urging the roller tube 12 outwards.

The caps 14 and 15 have several prongs 45 stamped from the side walls thereof and engaging openings 46 formed in the roller tubes for the purpose of assisting in holding said caps 14 and 15 in position. The tube 12 has several prongs 47 stamped from the side wall thereof and cooperative with small openings 48 formed in the tube 11 for limiting outward projection of the roller tube 12.

In Figs. 11 and 12 a modified form of the invention has been disclosed which distinguishes from the prior form in several respects. This window shade and screen roller has a pair of telescopically engaged roller tubes 10 and 11 which are formed with the longitudinally extending flutes 13 slidably connecting the same. A cup shaped cap 14 and its associated parts is mounted upon the outer end of the tube 10 similar to the arrangement disclosed in the preferred form of the invention, like parts being identified by like reference numerals. A cup shaped cap 15 is mounted upon the outer end of the tube 11.

A disc 40' has a flange 40^a with projections 41 engaging in small openings 42 formed in the material of the tube 10. This disc 40' has a hub portion 40^b through which a screw 50 is coaxially, threadedly engaged. This screw 50 supports a disc 55. A spring 43' is supported at one end 43^b to several loop shaped lugs 44' stamped from the material of the cap 15. The other end 43^a of the spring is free and rests against the disc 55. The disc 55 is welded or in any other way fixedly mounted on the screw 50.

In other respects this form of the invention is similar to the previous form and like parts are identified by like reference numerals.

The operation of the device is as follows:

A window shade or screen may be mounted upon the roller by engaging the edges beneath the prongs 16 and securing the prongs in position. The spring 30 will be wound up when the shade or screen is drawn and will re-wind the shade or screen as desired. The ratchet 24 and pawls 28 will cooperate to hold the shade or screen extended. If desired, the screen may be attached to one edge of the sash of the window, and in that case the pawl and ratchet must be rendered inoperative. This can be done by turning around the bracket 26 as previously explained.

Because of the fact that the peg 17 and the non-circular peg 23 are disposed within the caps 15 and 14 respectively, the ends of the roller will engage quite close to the sides of the window frame. Thus the edges of the shade will be correspondingly located.

A feature of the first form of the invention resides in the fact that the roller tubes 10 and 11 may be relatively adjusted to windows of different widths. The tube 12 is resiliently supported so that it may be forced inwards at any time that it is desired to mount or remove the roller from the window frame.

A feature of the invention shown in Fig. 11 is the fact that the tubes 10 and 11 may be separated, and then the screw 50 adjusted to any extended or retracted position to approximately ad-

just the overall length of the roller when these tubes are reassembled. The spring 43' engages against the disc 55 to hold the roller 11 resiliently so that it may be forced inwards a small distance to permit the shade roller to be mounted or removed from position.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In an adjustable combination window shade and screen roller, a plurality of telescopically engaged roller tubes having interengaging longitudinally extending flutes extending from end to end, means for holding certain of the roller tubes in various adjusted positions, and means for resiliently connecting certain of said roller tubes.

2. In an adjustable combination window shade and screen roller, a plurality of telescopically engaged roller tubes having interengaging longitudinally extending flutes extending from end to end, means for holding certain of the roller tubes in various adjusted positions, and means for resiliently connecting certain of said roller tubes, comprising a disc mounted across one of the roller tubes and supporting a resilient member indirectly connected with another one of the roller tubes.

3. In a combination window shade and screen roller, a plurality of telescopically engaged roller tubes having interengaging longitudinally extending flutes extending from end to end, means for holding certain of the roller tubes in various adjusted positions, and means for resiliently connecting certain of said roller tubes, comprising a disc mounted across one of the roller tubes and supporting a resilient member indirectly connected with another one of the roller tubes, said resilient member comprising a spring.

4. In a combination window shade and screen roller, a plurality of telescopically engaged roller tubes having interengaging longitudinally extending flutes extending from end to end, means for holding certain of the roller tubes in various adjusted positions, and means for resiliently connecting certain of said roller tubes, said means for holding certain of said roller tubes in various

adjusted positions comprising a resilient element mounted on one of the tubes and cooperative with openings formed in the other of the tubes, said resilient element comprising a leaf spring which is mounted through H-shaped openings in one of the tubes.

5. In a combination window shade and screen roller, a plurality of telescopically engaged roller tubes having interengaging longitudinally extending flutes extending from end to end, means for holding certain of the roller tubes in various adjusted positions, and means for resiliently connecting certain of said roller tubes, said means for holding certain of said roller tubes in various adjusted positions comprising a resilient element mounted on one of the tubes and cooperative with openings formed in the other of the tubes, said resilient element comprising a leaf spring which is mounted through H-shaped openings in one of the tubes, and has projections engageable with certain of a series of openings in the other tube.

6. In a combination window shade and screen roller, a plurality of telescopically engaged roller tubes having interengaging longitudinally extending flutes extending from end to end, means for holding certain of the roller tubes in various adjusted positions, and means for resiliently connecting certain of said roller tubes, said means for holding certain of said roller tubes in various adjusted positions comprising a disc mounted across one of the tubes, a screw threadedly engaged through said disc, a disc mounted on said screw, and a member disposed between said disc and a stationary portion of the other of said tubes.

7. In a combination window shade and screen roller, a plurality of telescopically engaged roller tubes having interengaging longitudinally extending flutes extending from end to end, means for holding certain of the roller tubes in various adjusted positions, and means for resiliently connecting certain of said roller tubes, said means for holding certain of said roller tubes in various adjusted positions comprising a disc mounted across one of the tubes, a screw threadedly engaged through said disc, a disc mounted on said screw, and a member disposed between said disc and a stationary portion of the other of said tubes, said member comprising a spring and constituting said means for resiliently connecting certain of said roller tubes.

ALFRED ZAFERAKIS.
